UNITED STATES PATENT OFFICE.

EDWARD E. COTÉ, OF HOLLAND, MICHIGAN, ASSIGNOR, BY MESNE ASSIGNMENTS, TO UNITED SHOE MACHINERY CORPORATION, OF PATERSON, NEW JERSEY, A CORPORATION OF NEW JERSEY.

ART OF SHOEMAKING.

Application filed June 19, 1914, Serial No. 846,111. Renewed April 17, 1925.

To all whom it may concern:

Be it known that I, EDWARD E. COTÉ, a citizen of the United States, residing at Holland, in the county of Ottawa and State 5 of Michigan, have invented certain Improvements in the Art of Shoemaking, of which the following description, in connection with the accompanying drawings, is a specification, like reference characters on the drawings indicating like parts in the several 10 figures.

This invention relates to improvements in the art of shoemaking and particularly to the manufacture of boots and shoes having 15 fasteners such as blind or invisible eyelets.

An "invisible eyelet" is an eyelet set in the lining portion of a shoe upper beneath the leather or outer portion of the upper and in register with a hole through the 20 leather portion which permits the passage of the lacing. The term "blind eyelet" is employed to designate an eyelet set in the outer portion of an upper in register with a hole in the lining portion.

25 Blind and invisible eyelets are preferably set after the layers of the shoe upper have been stitched together, the setting being performed by means of a setting tool introduced from one side of the shoe upper through a lacing hole so that, by relative movement of the tool and the shoe upper, the clenching shoulder of the tool is positioned between 30 adjacent layers of the shoe upper where it meets the entering end of the eyelet barrel. 35 and clenches the eyelet between the layers. In inserting eyelets in this fashion difficulty has been experienced in locating the clenching shoulder of the tool with respect to the layers of the shoe upper with the result 40 that the prongs of the eyelet barrel have sometimes failed to clench in the proper position between the layers. For example, if the upper leather passes too far beyond the clenching shoulder of the tool, the eyelet will clench between the lining or facing 45 and the reinforcing stay, or partly beneath and partly above the stay, thus reducing the holding power of the eyelet.

50 It is, accordingly, an object of my invention to provide an improved method of inserting fasteners and clenching the ends of their barrels between adjacent layers of material in a manner which will cause the entering ends of the barrels of the fasteners

to be properly clenched in the desired position between the layers. With this object in view, when inserting fasteners in accordance with the present invention, relative movement of the setting tool and the outer layer of the material is positively arrested 55 when the clenching shoulder of the tool has been properly positioned between the layers of the work, and this relation of the tool and the work is maintained during the 60 clenching of the fasteners. 65

In my prior co-pending application Serial No. 819,835 filed February 19, 1914 I have disclosed and claimed eyelet setting mechanism in the use of which my improved method may be carried out, but it should be understood that the practice of this novel 70 method is not restricted to the use of this particular eyelet setting mechanism. In the accompanying drawings certain steps of my improved method are illustrated in connection with the mechanism of my prior application above noted, and in these drawings, 75

Figs. 1 and 2 illustrate respectively portions of the leather and lining parts of an upper before they are secured together; 80

Fig. 3 illustrates the securing of the parts together;

Fig. 4 is a view, partly in section, of punching and eyelet inserting tools illustrating their use in the performance of the novel 85 method:

Fig. 5 is a view in perspective of the setting tool, and

Fig. 6 shows a portion of an upper in which invisible eyelets have been set. 90

As herein disclosed, the lining parts of the upper are prepared in the usual manner. The leather part 30 as shown in Fig. 1 is prepared by having the edges which are to be exposed in the finished shoe folded back 95 upon the body of the blank. The lining part 32, as shown in Fig. 2, is cut approximately to the size of the leather part and a reinforcing strip 33 of heavy canvas or similar material is cemented to the inner surface 100 of the lining in the proper position to receive the eyelets and thus afford them an additional holding.

After the parts have been so prepared the leather portion is placed upon the lining part with the edge of the lining registering with the edge of the leather part or projecting slightly beyond. The parts are then se-

cured permanently in that relation which they are to occupy in the finished shoe by a line of stitching 27 extending entirely about the edges of the upper which are to be exposed. The forward or lacing slit edge of the upper is, of course, one of these edges and is stitched up, as also is the top edge of the upper and the other exposed edge. The stitching operation is usually combined with 5 an operation known as "undertrimming" which consists in trimming off the surplus margin of the lining part. As shown in Fig. 3, the needle bar 24 of the sewing machine is equipped with a trimming blade 26 for this 10 purpose.

The lacing holes are next punched entirely through both parts of the upper and the eyelets inserted. The holes punched in the leather or outer portion remain to be seen in 15 the finished shoe while the invisible eyelets are set in the holes formed in the lining portion with their flanges inside the shoe and the ends of their barrels clenched on the lining beneath the leather or outer part. 20 As herein exemplified, after each lacing hole has been punched, the eyelet setting tool is inserted into the hole from one side of the upper and the eyelet is introduced from the other side. The entering end of the eyelet 25 barrel is then forced against the clenching shoulder of the tool and clenched between the layers of the work. Relative movement of the tool and the work during the clenching operation is limited by a flange or abutment 30 carried by the tool so as to ensure the clenching 35 of the eyelet between the desired layers.

The practice of my improved method will now be described as carried out in the operation of such mechanism as that disclosed in 40 my prior application above referred to.

Referring to Figs. 4 and 5 of the drawings, a punch 20 is shown as arranged to co-operate with a punching die 22 to perforate the work resting on the table 19 which may be 45 the work table of any well-known eyeleting machine as fully explained in said application. At one side of the punching tool the setting tools are arranged. The work is advanced after each hole is punched to bring 50 that hole into alignment with the setting tools.

The lower or eyelet carrying set 16 is provided with the usual center spindle 18 and acts to present an eyelet to the work and insert its barrel through the previously 55 punched hole in the lining part of the upper which rests upon the table 19. The clenching surface of the illustrated tool which may be utilized in carrying out this method is constructed and arranged so as to permit its introduction through the hole in the leather or outer part of the upper by relative movement of the tool and the shoe upper. This 60 tool has a heavy and rigid flange 10, illustrated as integral with the tool, and is also 65

provided with a solid spindle having a shouldered portion 12 and a leader or pilot 14 of reduced diameter. The end surface of the shoulder, that is the surface joining the cylindrical surface of the portion 12 and the surface of the leader 14, is shaped to act as a clenching surface, being curved as shown in cross-section in Fig. 4. The construction of the tool is such that when it is inserted from the outer side by relative movement of 70 the tool and the shoe upper, the portion 12 will fill the hole in the outer layer of the upper and the end surface of the clenching shoulder will be disposed approximately 75 flush with the inner surface of the outer or leather portion of the upper. The lower surface of the flange 10 at the same time bears upon the outer surface of the leather part 30.

In using the mechanism herein illustrated 80 in the practice of the present method, the shoe upper is perforated by the punch 20 which is then withdrawn to permit the introduction of the setting tool into the lacing hole. The setting tool is utilized to feed 85 the work so as to bring the lacing hole into alignment with the lower set which is then moved upwardly, introducing an eyelet into the lacing hole. The entering end of the eyelet barrel is thus forced against the 90 clenching shoulder of the upper set and continued relative movement of the eyelet and the upper set clenches the eyelet barrel between adjacent layers of the work as illustrated in Fig. 4. During this clenching operation relative movement of the upper set and the outer layer of the work is positively arrested by the engagement of the work against the abutment or flange 10 of the setting tool so as to ensure the correct positioning 95 of the clenching surface of the shoulder between the reinforcing stay 33 and the upper leather 30. Thus the end of the eyelet barrel is properly clenched upon the covered surface of the lining part or reinforcing strip which constitutes a portion of the lining. In this operation the clenching shoulder acts to roll outwardly the end of the eyelet barrel while the lower surface of the flange 10 tends to flatten the clenched end 100 of the barrel by pressing the leather part of the upper against it.

Having now described the method of my invention, together with the product thereof and one form of apparatus for carrying out the method, I claim as new and desire to secure by Letters Patent of the United States:

1. That improvement in methods of inserting fasteners in a plurality of layers of material by a setting tool adapted to be inserted through the layers of the material so as to clench a fastener between adjacent layers of the material characterized by the fact that the movement of the outer layer 115

of the material relatively to the setting tool is positively arrested when the clenching shoulder of the tool is in proper clenching position between the layers.

5. 2. That improvement in methods of inserting eyelets in a plurality of layers of material which comprises introducing a setting tool from one side of the material and an eyelet from the other side and positively

arresting the relative movement of the outer 10 layer of the material and the setting tool when the clenching shoulder of the tool is properly positioned with respect to the layers to clench the eyelet between adjacent layers of the material. 15

In testimony whereof I have signed my name to this specification.

EDWARD E. COTÉ.
